UNITED STATES PATENT OFFICE.

CHARLES E. SEEMAN AND LOUIS V. BARACH, OF PITTSBURGH, PENNSYLVANIA.

BILLIARD CUE.

Application filed October 12, 1922. Serial No. 593,996.

To all whom it may concern:

Be it known that we, CHARLES E. SEEMAN and LOUIS V. BARACH, citizens of the United States, residing at Pittsburgh, in the county of Allegheny and State of Pennsylvania, have invented certain new and useful Improvements in Billiard Cues, of which the following is a specification.

This invention relates to improvements in billiard or pool cues, more particularly to the points thereof and the objects thereof are to provide a novel form of cue point which embodies positive and reliable means for securing the cue tip thereto, and which includes a removable socket element permitting of its replacement when worn, such substitution providing for the economical prolonged use of the more expensive parts of the point associated therewith.

Further objects of the invention are to provide a cue point of the character stated, in a manner as hereinafter set forth, which is simple in its construction and arrangement, strong, durable and efficient in its use, attractive in appearance, readily attached in position to the cue, and comparatively inexpensive to manufacture.

With the foregoing and other objects in view, the invention consists of the novel construction, combination and arrangement of parts as hereinafter set forth and illustrated in the accompanying drawing wherein is shown an embodiment of the invention, but it is to be understood that changes, variations, and modifications can be resorted to which come within the scope of the claims hereunto appended.

In the drawing forming a portion of this specification and wherein like numerals of reference designate corresponding parts throughout the several views:—

Figure 1 is a side elevation of a cue equipped with our improved point, with a portion of the former broken away.

Figure 2 is a vertical sectional view of the point.

Figure 3 is a top plan view thereof.

Figure 4 is a side elevation of the socket element.

Figure 5 is a perspective view of the washer.

Referring in detail to the drawings 1 designates the tapering smaller end of a cue of a conventional form, which is ordinarily constructed from wood, but may be made from any other suitable materials.

The present invention resides in providing the cue with an improved point 2, and in Figure 2 of the drawings the preferred form thereof is illustrated, including an internally threaded ferrule 3. The latter is of the same outside diameter as the cue end against which it is mounted and extends flush therewith. The ferrule is preferably constructed from metal but ivory or other materials may also be used.

A socket plug 4, having its outer face formed with peripheral threads 5 is threadably mounted in the ferrule 3 and projects slightly beyond the lower end thereof. The socket plug projection 6 is formed to provide a flare upon which the threaded collar 7 is fixedly forced before the plug 4 is mounted in the ferrule 3. The plug 4 and the collar 7 are preferably constructed from fibre, but composition materials may also be successfully employed for these parts. The periphery of the collar 7 is flush with the outer face of the ferrule 3.

The socket plug 4 is further provided with an enlarged threaded bore of considerable depth forming the socket 8 into which the threaded tenon 9 of the cue is threadably attached. A small central bore 10 extends from the bottom of the socket 8 to the lower end of the plug 4, for the purpose to be described.

The lower face of the collar 7 is flush with the lower face of the socket plug 4 and these combined faces form the seat 11 upon which the cue tip 12 is adhesively secured.

The seat 11 is formed with a plurality of circular grooves 13 which together with the small bore 10 are designed for the purpose of providing seat surface recesses and inequalities capable of engaging the adherent agent, namely cement, etc., thereby assuring the fixed adhesion of the cue tip 12 upon the seat 11.

In a cue point of our improved construction the socket plug 4 may be readily replaced when the threaded socket 8 becomes worn from use. The socket plug can be manufactured at a nominal cost and such replacement will prolong the utility of the comparative expensive ferrule 3 associated therewith.

What we claim is:—

1. The combination with a tapering cue having a tenoned end, of a ferrule, a plug mounted in said ferrule, said tenoned cue end mounted in said plug, a collar secured

- to the lower end of said plug and forming a seat in conjunction therewith and a cue tip adhesively secured to said seat, said seats formed with recesses capable of augmenting the adhesive qualities of the agent connecting the cue tips to said seat, the lower end of said plug projecting from said ferrule and formed with a flare adapted for locking said collar in position on said plug.
10. 2. The combination with a tapering cue having a tenoned end, of a ferrule, a plug threadably mounted in said ferrule, said tenoned cue end threadably mounted in said plug, a collar threadably secured to the lower end of said plug and forming a seat in conjunction therewith, and a cue tip adhesively secured to said seat, said seat formed with recesses capable of augmenting the adhesive qualities of the agent connecting the cue tips to said seats, the lower end of said plug projecting from said ferrule and formed with a flare adapted for locking said collar in position on said plug.
15. 3. The combination with a tapering cue having a tenoned end, of a ferrule, a plug detachably mounted in said ferrule, said tenoned cue end detachably mounted in said plug, a collar detachably secured to the lower end of said plug and forming a seat in conjunction therewith, and a cue tip adhesively secured to said seat, said seats formed with recesses capable of augmenting the adhesive qualities of the agent connecting the cue tips to said seat, the lower end of said plug projecting from said ferrule and formed with a flare adapted for locking said collar in position on said plug.

4. The combination with a tapering cue having a tenoned end, a ferrule, a plug formed with a socket secured in said ferrule, said tenoned cue end engaged in the socket of the said plug, a collar attached to the lower end of said plug and forming a seat in conjunction therewith, and a cue tip adhesively secured to said seat, said seat formed with recesses capable of augmenting the adhesive qualities of the agent connecting the cue tips to said seats, the lower end of said plug projecting from said ferrule and formed with a flare adapted for locking said collar in position on said plug.
5. The combination with a tapering cue formed with a tenon at its smaller end, a ferrule provided with a threaded bore, a plug having peripheral threads mounted in said threaded ferrule, the lower end of said plug provided with a tapered projection extending from said ferrule, a collar threadably fixed on said tapered plug projection and forming a cue tip seat in conjunction with the lower face of the latter, said plug further formed with a threaded socket adapted for engagement with said tenoned cue end, and a cue tip adhesively mounted on said seat, said seat formed with a plurality of circular grooves and with a small bore for augmenting the adhesive qualities of the agent connecting said cue tips to said seat.

In testimony whereof we affix our signatures.

CHARLES E. SEEMAN.
LOUIS V. BARACH.
